SLIDING EXTENSION LEAF FOR TABLES
AND CABINETS

Tore H. Lindelöf, Stockholm, Sweden

Application November 17, 1949, Serial No. 127,883
In Sweden November 17, 1948

4 Claims. (Cl. 311—16.5)

1

The present invention relates to an arrangement in slides in tables, cabinets and the like, where the slide in its inactive position is inserted in a partition.

The invention has for its object to obtain a slide arranged to be operated in such a manner that in its withdrawn position it is swingable in the horizontal plane into different angular positions relatively to the partition, i. e. the table, cabinet or the like so that a more convenient working place is obtained at said slide.

Other objects of the invention will appear from the description with reference to the accompanying drawings.

Figure 1 shows, in plan view and on a reduced scale, a table provided with a slide arranged according to the invention, which slide is in a swing-out position.

Figure 2 is a front view, on the same scale, of the table, the slide being in inserted position.

Figure 3 is a side view, on an enlarged scale, of a swingable bracket arrangement.

Figure 4 shows on a reduced scale, the slide as viewed from below, the bracket arrangement being in the withdrawn position of the slide.

Figures 5 and 6 show, in the same manner as in Figure 4, the slide together with the bracket arrangement in two different positions during the insertion of the slide into its partition.

Figure 7 shows in real size an axial section through the bearing arrangement.

Figure 8 shows in cross section along the line 8—8 of Figure 7 a locking device combined with the bearing arrangement.

A piece of furniture, shown as a table or a cabinet 1 having a leg frame or walls 2, comprises a partition, below the top of the table, for a slide 3, which may be carried out in any desired manner or may consist of a frame. The slide 3 is guided in the partition in the conventional manner by means of ledges or the like. As appears from Figure 2, below the slide there are shown ledges 4, which are adaptable for guiding drawers, for example. Figure 1 shows the slide 3 in a swung-out position, which lies at an angle of nearly 180° to the position of the slide inserted in the partition. In the swung-out position the slide 3 is carried by a bracket 5 swingable about a vertical pin 6 provided near the fore edge of the partition. The bracket is provided with a sleeve shaped bearing member 7, which encloses the pin 6 and which may form part of one leg of the piece of furniture or part of the fore border of the piece of furniture, the outer surface of the sleeve 7 conforming, if desired, with the shape of

2

the leg or of said border. In the inserted position the slide is guided in the partition and released from the bracket. On the other hand, in the swung-out position the slide is connected with the bracket. According to the example shown, the bracket is in the form of a substantially triangular plate, one corner portion 8 of which in the swung-out position of the slide is introduced into a dark-slide like member 9 rigidly secured to the slide 3. As further appears from Figures 3 and 4, the dark-slide like member contains a marginal ledge 10, 11 bent to form a V, one branch 10 of which in the entirely drawn-out position of the slide bears against the triangular bracket 5 along one side thereof, whereas the other branch 11 is located adjacent a portion of another side 12 of the bracket 5. The bracket 5 is substantially in the form of a right-angled triangle so that the edge 12 extends along the hypotenuse of the triangle, whereas the edge 13 located adjacent the marginal edge 10 forms one of the small sides of the triangle. A prolongation of the ledge 11 is designated by 14. The ledges 10 and 11 are interconnected by means of a plate member 15, which together with the marginal ledges 10, 11 and the slide 3 forms a pocket intended to receive the corner portion 8 of the bracket. As stated above this takes place in the entirely drawn-out position of the slide, and hence said pocket is provided near the rear edge 16 of the slide 3. On the under side of the slide 3 at the fore edge there is a butt ledge 17 extending over the entire width of the slide.

Figures 5 and 6 show two different positions of the slide in the partition. According to Figure 5, the slide 3 is inserted half-way from the position shown in Figure 4. During this movement, the marginal ledge 11 has actuated the bracket 5 so that this latter is angularly displaced. The edge 12 of the bracket is nearly parallel to the longitudinal edges of the slide. The outer portion of the ledge 11 thus operates as a cam member. Hereafter, the slide 3 may be inserted a further distance, ere the bracket engages the butt ledge 17 on the slide and is angularly adjusted while moving through the position shown in Figure 6. In the entirely inserted position of the slide 3, the outer edge of the bracket is parallel to the butt ledge 17, while the edge 13 is nearly parallel to the longitudinal edge of the slide.

When the slide 3 is drawn out of the partition, the edge 12 of the bracket moves into engagement with the outer end portion of the ledge 14 and is angularly adjusted so that the edge 12 of

55

the bracket will be nearly parallel to the longitudinal direction of the slide. In the last-mentioned position the corner 8 impinges the ledge 10. When the slide 3 is further withdrawn, the corner 8 slides along the ledge 10, until finally the bracket and the pocket assume the position shown in Figure 4. During this movement, the ledge 10 operates as a guide bar.

In the final coupling position between the bracket 5 and the pocket 9, a bent end portion 18 of the ledge 10 passes into engagement with a recess 19 in the bracket so that the slide 3 is fixed laterally in relation to the bracket. At the same time a short pin 20 on the bracket engages a slit shaped recess 21 at the edge of the plate member 15. Said recess is so directed relatively to the pin 6 that the slide is locked in position relatively to the bracket so that the slide upon being rapidly swung out is prevented from being disengaged from the bracket.

In Figure 3 the bracket is seen in the direction towards the fore edge of the slide. On the side of the sleeve 7 facing said slide there is provided a locking member 22 pivotally mounted by means of a peg, said locking member being inserted in a slide shaped recess 23. As shown more distinctly in Figure 7, said locking member is actuated by a spring 24 which tends to hold the locking member in inserted, i. e. inactive position in which said member is located inside the contour of the sleeve 7. Adjacent the locking member 22, the pin 6 is bevelled and is here limited by a plane surface 25 which surface allows the locking member 22 to assume the inactive position shown, when the slide is in the withdrawn position in the partition. However, as soon as the slide is swung, the bearing sleeve 7 turns about the pin 6 and the locking member 22 engages the cylindrical surface of the pin 6, whereby the locking member is moved outwards into engagement with a recess 26 in the longitudinal edge of the slide. In this way, the slide is locked against movement in its longitudinal direction and is retained, during the movement of oscillation, in the position in which it is coupled to the pocket 9. When the slide has been returned to the angular position determined for insertion into the partition, the locking member 22 has been returned by the spring 24 into its inactive position and has moved out of engagement with the slide.

Of course, the locking member is moved outwards from the inactive position when the slide is inserted into the partition but during this movement the bearing sleeve 7 turns in relation to the slide so that the locking member is moved away from the slide.

Figure 8 shows the placement of the bearing sleeve 7 on the pin 6, the lower part of which is rigidly secured to the lower part of the thrust ball bearing 27 placed inside the piece of furni-

ture. The sleeve rests on said upper part 28 of said bearing and above it is centred by means of a ball bearing 29 provided in the upper end of the sleeve. The upper end of the pin 6 is rigidly secured to a plane fitting 30 screwed on to that upper portion of the piece of furniture which is located below the top of the table.

I. claim:

1. In combination with a table, cabinet or the like having a partition therein, a slide adapted to be slid into and out of the partition, guide means in the partition to guide said slide for horizontal movement into and out of the partition, cam members on the lower side of said slide, a vertical pivot near the outer edge of one side wall of said partition, a bracket journaled on said pivot and including a horizontal carrying surface adjacent to the lower side of said slide when located in the partition, said bracket including means engaging said cam members when the slide is drawn outwards from the partition thereby to cause the bracket to swing on the pivot, and connecting members on the slide and the bracket constructed and positioned to engage each other when the slide is drawn out of the partition and out of engagement with the guide means in the partition.

2. The combination claimed in claim 1, wherein in the outer edge of the slide is provided with a butt member adapted to engage the bracket and swing it back into the position in the partition when the slide is slid into the partition.

3. The combination claimed in claim 1, wherein in the cam members and the connecting means on the slide are integral with each other to form a unit mountable on the lower side of the slide.

4. The combination claimed in claim 1, wherein in the bracket is rigidly connected with a sleeve mounted on said pivot, said sleeve having a recess therein, a locking member normally held by spring pressure in an inactive position within the outer contour of the sleeve, a cam surface on said pivot 6 positioned to urge the locking member outwards beyond said contour when the slide is angularly displaced in relation to the partition, and a recess in the slide positioned to receive the locking member when so displaced.
